UNITED STATES PATENT OFFICE

167,120

FINGER RING

Vincent Sorrentino, Providence, R. I., assignor to
Uneas Manufacturing Company, a corporation
of Rhode Island

Application August 24, 1951, Serial No. 16,424

Term of patent 14 years

(Cl. D45—10)

To all whom it may concern:

Be it known that I, Vincent Sorrentino, a citizen of the United States of America, residing at Providence, county of Providence, State of Rhode Island, have invented a new, original, and ornamental Design for a Finger Ring, of which the following is a specification, reference being had to the accompanying drawing, forming a part thereof.

Fig. 1 is a top plan view of a finger ring, showing my new design;

Fig. 2 is a side view thereof; and

Fig. 3 is a edge view thereof.

My design for a finger ring is characterized by the heart-shaped elements flanking the three larger circular center stones in association with the two oppositely facing heart-shaped elements and the graduated crescent-shaped notches, all as shown.

I claim:

The ornamental design for a finger ring, substantially as shown and described.

VINCENT SORRENTINO.
